LAPPING MACHINE

Robert K. Kinard, Allentown, Pa., assignor to
Western Electric Company, Incorporated, New
York, N. Y., a corporation of New York

Application April 4, 1947, Serial No. 739,437

3 Claims. (Cl. 51—120)

1

This invention relates to lapping machines and more particularly to a machine for lapping extremely thin quartz crystal slices for use in electrical arts.

For various uses in electrical arts, it is necessary to employ small slices of crystalline quartz having their flat faces formed parallel with each other to an extreme degree of accuracy and the slices being further formed to a predetermined thickness with great accuracy. Such slices are rough cut and formed in various ways and are subsequently ground or cut to approximately the desired thickness. The final step of lapping these nearly finished slices down to the finished product is a difficult task, especially on a production basis. The most popular method of lapping quartz crystal slices includes a carrier or lapping nest comprising a metal disc oscillated between lapping plates supplied with an abrasive material, the carrier or nest having apertures therein to receive and control the movement of the slices between the lapping plates. The carrier or lapping nest of necessity had to be thinner than the final thickness desired for the quartz slices and also sufficiently durable to be driven to move the numerous quartz slices between the lapping plates.

Recently quartz crystal slices of a finer thickness than heretofore required have been requested for electrical units. This new thickness is approximately 25 microns and the crystal slices of this thickness could not be produced by the present lapping machines and methods. A lapping nest of a thickness suitable to accommodate these slices would not be sufficiently durable to be driven between the conventional lapping plates.

An object of the invention is to provide an improved apparatus for simultaneously lapping both sides of each of a plurality of thin objects to produce, to a high degree of accuracy, parallel plane faces spaced a predetermined distance apart.

With the above and other objects in view, the invention comprises a lapping machine including an element formed with a plurality of lapping surfaces surrounded by a retaining element and cooperating with a relatively movable lapping plate to lap objects disposed on the lapping surface. More specifically, the lapping machine includes a stationary element having a circular arrangement of vertically extending lapping members, cylindrical in general contour, equally spaced from each other and having hardened gridded upper surfaces. A retaining element an-

2

nular in general contour has a series of openings to receive the projections, the upper surface of the retaining element being positioned a given distance above and parallel with a common plane in which the gridded surfaces are disposed, this distance being less than the final thickness of the objects. A lapping plate is supported loosely upon the objects to be lapped and is oscillated relative to the lapping members, additional means being provided to create an additional motion in the lapping plate to vary the portions of the gridded under surface thereof which come in contact with the objects being lapped.

Other objects and advantages will be apparent from the following detailed description when considered in conjunction with the accompanying drawings, wherein

Fig. 1 is a vertical sectional view of one of the species of the invention;

Fig. 2 is a fragmentary top plan view of the structure shown in Fig. 1, portions thereof being broken away;

Fig. 3 is a fragmentary sectional view taken along the line 3—3 of Fig. 2; and

Fig. 4 is a vertical sectional view of another species of the invention.

Referring now to the drawings, attention is first directed to Figs. 1 to 3, inclusive. The species of the invention shown in these figures includes a supporting frame 10 having a saucer shaped table 11 mounted thereon with central bosses 12 and 14 positioned about a central aperture 15 for a shaft 16. An annular element 18 formed with a plurality of cylindrical lapping members 19 formed integral therewith is mounted centrally of the table 11.

The upper surfaces of the lapping members 19 are hardened and ground to lie in a common plane, these surfaces also being gridded as at 20. A retaining element 21, annular in general contour has a series of apertures 22 therein substantially equal in diameter to the diameter of each of the lapping members 19 to receive these members as illustrated in Figs. 1 and 2. The thickness of the retaining element 21 is slightly greater than the height of the lapping members 19, the difference in thickness being less than the desired final thickness for the objects or quartz crystal slices to be produced by this machine.

An upper lapping plate 25 is cylindrical in general contour, its diameter being greater than the diameter of the retaining element 21. The under surface 26 of the lapping plate is hardened

and gridded in the conventional manner as indicated at 27.

The driving means for the lapping plate 25 includes the shaft 16 which is journalled in bearings 28 and 30 within the bosses 12 and 14 and the central aperture 15 of the table 11. The shaft 16 is further supported by a thrust bearing 31 disposed in a lateral member 32 of the main frame 10. A beveled gear 33 mounted upon the shaft 16 is driven from a main drive shaft 34 through a beveled gear 35. A collar or head 36 mounted upon the upper end of the shaft 16 carries a pin 37 eccentrically mounted to move in a circular path, the diameter of which is substantially equal to the diameter of each of the lapping members 19. The pin 37 extends vertically through a bearing 38 centrally positioned in the lapping plate 25.

In addition to the motion imparted to the lapping plate 25 through its driving mechanism, an additional motion is desired to be imparted thereto to eliminate the possibility of continuous wear on limited parts of the gridded face of the lapping plate. This additional moving means includes sprocket-like teeth 40 mounted on the periphery of the lapping plate 25 to be engaged by a cushioned roller 41 as the lapping plate moves outwardly in this direction during each cycle of movement. The roller 41 is supported by an arm 42, slidably disposed in an aperture 43 of a holder 44, limited in its movement by a pin 45 and normally urged outwardly by a spring 46, the spring functioning to cushion the contact between any of the teeth 40 of the lapping plate 25 and the roller 41.

Prior to considering the operation of the machine, attention is directed to the objects 50 which are to represent quartz crystal slices to be reduced in thickness by this machine to approximately 25 microns. The objects 50 in reality are slightly thicker than the required final dimension before they are placed in their respective pockets on the lapping members 19. It will be observed therefore that the dimensions of the objects 50, the distances between the upper surfaces of the lapping members 19 and the retaining element 21, as well as the distance between the lapping plate 25 and the lapping members 19 are greatly exaggerated only to clearly illustrate the existence of pockets formed in the apertures 22 of the element 21 above the lapping members 19 and also to illustrate the existence of parts 50 within these pockets. The lapping machine as illustrated in the drawings is of necessity smaller than the actual machine. It would not be possible to show the objects 50 in the drawings with their exact thickness and the same applies to the illustration of the depth of the pockets receiving the objects and the space between the lapping surfaces.

In preparing the machine for operation the lapping plate 25 is removed and an object, namely, a quartz crystal slice 50, is placed within each of the pockets, that is, the apertures 22 above the gridded surfaces of the lapping members 19. The lapping plate 25 is then carefully lowered in place and the conventional abrasive material is supplied in the usual manner to the lapping areas during operation of the machine. The saucer shaped formation of the table 11 is to receive the abrasive material and direct it in the usual manner to the supply (not shown). The machine is then set in operation by driving the shaft 34, causing rotation of the shaft 16 through the gears 33 and 35, causing the pin 37 to move in its cir-

cular path about the centerline of the shaft 16 to oscillate the lapping plate 25 relative to the lapping members 19. This action will cause both lapping surfaces adjacent each object 50 to grind away the surfaces of the object through the assistance of the abrasive material, maintaining the surfaces parallel with each other. Each time the lapping plate 25 approaches the roller 41, the roller will engage one of the teeth 40 and act as a fulcrum for the lapping plate during the continued movement applied to the lapping plate through the pin 37, creating intermittent adjustments in the lapping plate relative to the lapping portions 19.

The species of the invention shown in Fig. 4 is identical in every detail to that shown in Figs. 1 and 2 with the exception of the driving means for the lapping plate, like reference numerals being applied to the like parts. The lapping plate in this figure is given the reference numeral 55, although it differs from the lapping plate 25 only in its connection with the driving means. The driving means in this instance includes a hollow shaft 56 journalled in a suitable bearing 57 and keyed to a pulley 58 driven by a belt 59 from a power means (not shown). If desired, the driving means may include a drive shaft operatively connected to the shaft 56 through the aid of gears as illustrated in Fig. 1. An arm 60 is keyed to the upper end of the shaft 56 and supports a pin 61 in the form of a shaft, the lower end of which is journalled in a bearing 62 of the arm 60. The axes of the shafts 56 and 61 are parallel with each other and disposed a given distance apart which is substantially equal the radius of the lapping members 19. A gear 64 fixedly mounted upon the pin or shaft 61 interengages a pinion 65 which is mounted upon the upper end of a fixed shaft 66 extending through the hollow shaft 56 into an apertured portion 67 of a lateral member 68 of the main frame 10. The aperture 69 is internally splined to receive the splined end 70 of the shaft 66. Returning now to the shaft 61, it will be observed that the upper end thereof is grooved at 72 to receive an apertured end of an arm 73 which is pivotally connected at 74 to the shaft 61. The outer end of the arm 73 is bent downwardly at right angles as indicated at 75 and is receivable in an aperture 76 in the lapping plate 55.

During operation of this species of the invention, through the driving of the belt 59, the hollow shaft 56 will be rotated about the stationary shaft 66 moving the pin or shaft 61 in a circuitous path to impart a circular or oscillating motion to the lapping plate 55 relative to the lapping members 19 and the objects 50. As the arm 60 carries the shaft 61 in its circuitous path, the gear 64 travels about the pinion 65 and in engagement therewith to cause the shaft 61 to rotate slowly. In this manner, there is a continuous change in the portions of the gridded surface 78 of the lapping plate 55 which come in contact with the various objects 50 to cause uniform wear on the lapping surface 78. Through this driving mechanism the same circular motion is imparted to the lapping plate 55 as is applied to the lapping plate 25 of the structure shown in Figs. 1 and 2. The only difference in the motions of the two lapping plates is that the adjusting motion of the lapping plate 55 is continuous while the adjusting motion of the lapping plate 25 is intermittent.

With these structures, their principal features being identical in the provision of a plurality of

fixed position lapping members with retaining pockets for the individual objects or thin quartz crystal slices, it is possible to reduce the thickness of these objects to fine dimensions while maintaining their faces or opposing surfaces substantially parallel. The fineness in the dimensions attained through this lapping process through the aid of the species of the lapping machine is made possible mainly through the sturdy structures forming the pockets and controlling the positioning of the quartz slices within their individual lapping areas. Furthermore, the lapping members, being integral with their base 18, may be simultaneously reconditioned and their surfaces maintained in a common plane. The retaining element 21 may be reconditioned in a similar manner grinding the upper surface thereof to maintain the depth of the pockets surrounding the gridded surfaces 20. Furthermore, the depth of the pockets may be varied by the introduction of shims between the abutting surfaces of the retaining element 21 and the base 18 of the lapping members 19.

Although specific improvements of the invention have been shown and described, it will be understood that they are but illustrative and that various modifications may be made therein without departing from the scope and spirit of this invention as defined by the appended claims.

What is claimed is:

1. An apparatus for simultaneously lapping opposite faces of thin articles comprising a plurality of lapping members disposed in circular arrangement at spaced positions with respect to each other and having upper surfaces to receive the articles to be lapped, means surrounding the lapping members to form retaining pockets above the upper surfaces of their respective lapping members of like depths less than the final thickness to which the articles are to be lapped, a lapping element positioned above the lapping members and having an under surface to engage all the articles simultaneously, and means to move the lapping element about an axis in a path the diameter of which is substantially equal to the diameter of each of the upper surfaces of the lapping members.

2. An apparatus for simultaneously lapping opposite faces of thin articles comprising a stationary support, an annular element mounted on the support and having integral lapping members circular in cross-section disposed in spaced positions circularly about the upper surface of the annular element with their upper surfaces gridded and positioned in a given plane parallel with the upper surface of the annular element, an annular retaining member, having a circular arrangement of cylindrical apertures therein to receive their respective lapping members, mounted on the upper surface of the annular element and being of greater vertical dimension than the lapping members whereby retaining pockets formed in the apertures extend above the gridded surfaces of like distances less than the

final thickness to which articles disposed individually in the pockets are to be lapped, a lapping element positioned above the lapping members and having a gridded under surface to rest on all the articles in the pockets simultaneously, and means to move the lapping element relative to the lapping members to lap the articles as they are individually retained in their respective pockets.

10 3. An apparatus for simultaneously lapping opposite faces of thin articles comprising a stationary support, an annular element mounted on the support and having integral lapping members circular in cross-section disposed in spaced positions circularly about the upper surface of the annular element with their upper surfaces gridded and positioned in a given plane parallel with the upper surface of the annular element, an annular retaining member, having a circular arrangement of cylindrical apertures therein to receive their respective lapping members, mounted on the upper surface of the annular element and being of greater vertical dimension than the lapping members whereby retaining pockets formed in the apertures extend above the gridded surfaces of like distances less than the final thickness to which articles disposed individually in the pockets are to be lapped, a lapping element positioned above the lapping members and having a gridded under surface to rest on all the articles in the pockets simultaneously, spaced projections mounted on the periphery of the lapping element, means to move the lapping element about a center coaxial with the center of the annular element in a path substantially equal to the like diameters of the lapping members, and means mounted on the support to be engaged by certain of the projections during each cycle of movement of the lapping element to impart further movement to the lapping element to vary the portions of the under surface of the lapping element engaging the articles to cause uniform wear on the said surface.
